VENETIAN BLIND CORD AND TASSEL DISPLAY DEVICE

Joseph A. Anderle, Westerleigh, N. Y., assignor to Levolor
Lorentzen, Inc., New York, N. Y., a corporation of
Delaware

Application March 18, 1955, Serial No. 35,100

Term of patent 14 years

(Cl. D21—1)

The single figure is a perspective view of a Venetian blind cord and tassel display device, showing my new design. The cords are lined for color.

I claim:

The ornamental design for a Venetian blind cord and tassel display device, substantially as shown and described.
